UNITED STATES PATENT OFFICE.

JUSTIN R. GRAVES, OF SIOUX FALLS, DAKOTA TERRITORY.

HEATING-STOVE.

SPECIFICATION forming part of Letters Patent No. 250,067, dated November 29, 1881.

Application filed May 2, 1881. (No model.)

To all whom it may concern:

Be it known that I, JUSTIN R. GRAVES, of Sioux Falls, in the county of Minnehaha and Territory of Dakota, have invented certain 5 new and useful Improvements in Coal-Burning Heating-Stoves; and I hereby declare the following to be a full, clear, and exact description thereof, which will enable others skilled in the art to which my invention appertains to make 10 and use the same, reference being had to the accompanying drawings, forming a part hereof, and in which—

Figure 1 represents a longitudinal central section of a self-feeding coal-burning heating- 15 stove with my improvements attached. Fig. 2 represents a detached view of the sprinkler *g*, shown in side elevation; and Fig. 3 represents a plan view of the same. Fig. 4 represents a side elevation of a modification of the 20 sprinkler *g* in the form of a flat disk.

Like letters of reference indicate like parts.

My invention consists in an apparatus adapted to sprinkle, and thereby keep cool, the unignited portions of coal in either the magazine 25 of a self-feeding stove, or in the fire-pot of a heating-stove, constructed substantially as hereinafter described.

In the drawings, *A* represents the shell of the upper part of a heating-stove, provided 30 with a magazine, *B*, which is covered with a lid, *i*, in the usual manner.

To the lid *i*, and so as to form a part thereof, is attached an urn, *D*, the stem of which is tubular and provided with a cock, *f*, and in the 35 under part of the foot of the urn is placed, and fastened thereto in any well-known man-

ner, a sprinkler, *g*, which may be made either conical, as shown in Fig. 2, with its apex truncated, or flat, as shown in Fig. 4, and provided in each case with a series of small holes, 40 *h*. In use the urn *D* is filled with water, and the cock *f* is turned so as to allow the requisite amount of water to flow through the tube *e* and fall upon the truncated apex of the sprinkler *g*, which causes it to scatter and fall over 45 and run down the sides of the cone and fall through the holes *h* upon the top of the coal *c* in the magazine, which, when properly regulated, will tend to keep it cool and moist without dampening the fire, and thereby prevent 50 the roasting out and escape of gases contained in the unignited coal until it reaches the fire-pot, where it becomes ignited and gives out its useful effects, and such treatment of the coal also tends to prevent, in a measure, the quantity 55 of soot and thick smoke incident to the use of soft coal.

Having thus described my invention, what I claim as new, and desire to secure by Letters Patent, is—

1. In combination with a coal-burning stove, a water reservoir or urn provided with a sprinkler, *g*, substantially as and for the purpose specified.
2. In combination with a coal-burning stove, 65 a water urn or reservoir, *D*, provided with a tube, *e*, cock, *f*, and sprinkler, *g*, substantially as shown and described.

JUSTIN R. GRAVES.
